CLAIM

The ornamental design for an accessory holder for a chair back, as shown and described.

DESCRIPTION

FIG. 1 is a front perspective view of an accessory holder for a chair back embodying my new design;

FIG. 2 is a top plan view thereof;

FIG. 3 is a front view thereof;

FIG. 4 is an end elevational view thereof taken from a first end;

FIG. 5 is an end view thereof from an end opposite FIG. 4;

FIG. 6 is a rear view thereof; and,

FIG. 7 is a bottom view thereof.

The broken lines shown in the drawings are for illustrative purposes only and form no part of the claimed design.
